FOOD GRINDER GUARD

Vincent G. Biro, Marblehead, Ohio, assignor to
Biro Manufacturing Company, Marblehead,
Ohio, a corporation of Ohio

Application February 9, 1954, Serial No. 28,927

Term of patent 14 years

(Cl. D55—1)

To all whom it may concern:

Be it known that I, Vincent G. Biro, a citizen of the United States, residing at Marblehead, in the county of Ottawa and State of Ohio, have invented a new, original, and ornamental Design for a Food Grinder Guard, of which the following is a specification, reference being had to the accompanying drawing, forming a part thereof.

Figure 1 is a perspective view of a food grinder guard embodying my new design. Figure 2 is an enlarged plan view of the food grinder guard shown in Figure 1. Figure 3 is a side view of the food grinder guard shown in Figure 2.

The grinder shown in broken lines is for illustrative purposes only.

I claim:

The ornamental design for a food grinder guard, as shown and described.
